LIGHTING FIXTURE

Filed April 8, 1931

UNITED STATES PATENT OFFICE

GEORGE ARRAS AND DWIGHT E. WORRELL, OF CHICAGO, ILLINOIS

LIGHTING FIXTURE

Application filed April 8, 1931. Serial No. 528,810.

This invention relates in general to an electric lighting fixture and has more particular reference to the supporting, attaching and adjusting means for connecting the various parts of a lighting fixture together.

One of the principal objects of the invention is in the provision of an apertured supporting cap for the fixture, permitting illumination of a portion of the space adjacent the cap. A further object of the invention is in the provision of a supporting cap having a weather-tight top with inside supports for adjustably mounting a lamp socket therein. Another object of the invention is in the provision of improved means for attaching a lamp shade and globe together without danger of cracking the globe. A further object of the invention is in the provision of quick detachable means for connecting a shade or reflector to a supporting cap.

Other and further objects will appear hereinafter, the drawing illustrating a preferred embodiment of the invention.

In the drawing Fig. 1 is a sectional view of a fixture constructed in accordance with the principles of this invention; Fig. 2 is a section taken on the line 2—2 of Fig. 1; Fig. 3 is a sectional view showing the connection between the shade and globe; Fig. 4 is a detail perspective of one of the fastening connections between the shade and the holder cap; and Fig. 5 is a section of one of the holders taken on the line 5—5 of Fig. 4.

In a lighting fixture it is desirable to provide a shade or reflector and a globe for enclosing the lamp which may be removed easily from supporting part of the fixture to permit access to the lamp for cleaning, renewal and repair. In lighting fixtures of this type it is also desirable to change or alter the lamps used and with larger lamps an adjustment is frequently necessary to obtain the best lighting effects.

It is also desirable when using opaque reflectors to provide some means for illuminating the space above the reflector to obviate a dark ceiling. In some cases this has been done by providing perforations around the upper edge of the shade or reflector, but in the present case the lower edge of the supporting cap is provided with openings through which the light rays may project. The present invention also provides a quick detachable connection between the supporting cap and the reflector such that the mov-

ing of a single spring catch will release the reflector for rotative movement by which it is disconnected from the cap.

Referring now more particularly to the drawing, the fixture is supported by a metal cap or holder 6 having a threaded upper end for receiving a conduit pipe 7 and with a squared or hexagonal portion 8 at this end to assist in attaching the cap to the conduit. At the lower edge of the cap portion are outwardly extending legs 9 supporting a holding ring 10 and providing unobstructed spaces between the legs through which light will shine from an electric lamp 11. To cover the spaces between the legs 9 a circular transparent piece 12 of glass or other suitable material is inserted within the cap 6 and is held in place within the angular ring 10 by fastening screws 13.

The lamp 11 is inserted in a socket 14 adjustable in the cap 6 upon parallel rods 15 and notches or grooves 16 at intervals engaged by clamps 17 held in place by screws 18 reached from the under or exposed side of the socket 14 and loosened or tightened from the open end of the cap 6 for adjusting the height of the socket therein. By this means an electric lamp mounted in the socket may be raised or lowered to obtain the best or desired results with the reflecting and light transmitting members of the fixture.

A transparent globe 20 of glass is provided to enclose the lower portion of the lamp 11, and a reflector 21 of metal extends outwardly from the globe and is secured thereto and to the supporting ring 10. The reflector support comprises a number of equally spaced lugs 22 extending from the holder ring 10, each having an inclined surface 23 and a number of plates 24 attached to the top of the reflector and projecting upwardly into the path of the lugs 22. Each plate has a slot 25 for engaging one of the lugs 22, and one of the plates having a spring catch 26 (see Fig. 5) with a slot 27 therein to engage in one of the lugs 22 bendable outwardly at its free end to release the lug from engagement with its slot 27 and having a curled outer extremity 28 providing a finger hold for moving the catch outwardly. In order to prevent the catch from accidental disengagement with any one of the lugs 22, a guard 29 projects over the outer edge of the catch having a free extremity which may be flexed outwardly if necessary by engagement of the

catch 26 therewith to admit and release the lug 22 engaged thereby. The plate 24, the catch 27 and the guard 29 are secured together by rivets 30 and each of the plates 24 is attached to the upper edge of the reflector 21 by one or more rivets 31.

In order to attach the globe 20 to the reflector, a resilient strip 32 of metal is attached intermediate its ends at one side of the reflector by fastening means 33 and the extremities 34 are bent upon themselves to provide rounded contact portions adapted to engage a reduced or neck portion 35 about the upper edge of the globe. At the opposite side of the reflector is a movable contact piece 36 having extremities 37 adapted to engage the neck 35 of the globe at some distance from the center thereof and to the central portion is connected a threaded stem 38 which extends through the rim of the reflector 21 and has a nut or head 39 at the outer end for adjusting the engagement of the contact piece 36. A set screw 40 in the form of a winged nut is threaded on the stem 38 and movable to engage the rim of the reflector 21 for holding the stem against accidental movement in any adjusted position.

With this construction the globe 20 may be removed separately from the reflector 21, the reflector and the globe may together be removed from the holder ring 10 and a lamp may be adjusted in height and removed either separately or with its socket by simply removing the globe 20, leaving the heavy and cumbersome reflector 21 in place. Light from the lamp 11 is diffused and reflected downwardly by the globe 20 and the inner surface of the reflector 21 and the space above the reflector and surrounding the cap is illuminated through the transparent piece 12 and between the cap is illuminated through the transparent piece 12 and between the legs 9. The cap 6, legs 9 and ring 10 are preferably cast in one piece so that this fixture when properly assembled is closed to prevent the entrance of dirt, insects and the like which decrease the efficiency of the light, and all of the parts are readily detachable from the cabinet and holder for cleaning, renewal and repair.

I claim:

1. A lighting fixture comprising a member with a supporting ring having spaced lugs, a reflector having spaced projections with slots to engage the lugs, and resilient means also carried by the reflector having a slot to engage over one of the lugs and adapted to be flexed outwardly for releasing the lug.

2. The combination with a structure as set forth in claim 1, of a flexible guard extending over and engaging the lug where the cap is located to prevent accidental disengagement of the catch, the flexing of the catch

also flexing the guard to allow disengagement of the lug.

3. In a lighting fixture, a member having a supporting ring with projecting lugs each inclined on one side, of a reflector having projections with slots adapted to be engaged by the lugs, a resilient slotted catch in connection with one of the projections adapted to be flexed outwardly by any one of the inclined surfaces of the lugs as the shade is engaged with the holder, the catch being bendable outwardly to free the engaged lug therefrom.

4. In a lighting fixture, a support, a reflector removably attachable thereto, a globe having a reduced neck portion for attachment to the reflector, and means comprising a spring strip attachable intermediate its ends to the reflector and having rounded extremities for engaging spaced points on the neck of the globe, and an opposite contact member having spaced extremities and a screw threaded stem extending through the reflector and attached to the central portion of the contact member movable to press the globe against the yielding member.

5. In an electric fixture, a yielding globe support comprising a supporting rim, a spring member attached intermediate its ends to the rim having its extremities extending inward therefrom to engage the reduced portion of the globe, a threaded member extending through the rim at the opposite side, a contact member attached intermediate its ends to the inner end of the threaded member, the extremities only of the contact member being adapted to engage the reduced portion of a globe, a head for adjusting the threaded member, and a lock nut for locking the threaded member in place against the rim.

6. In a lighting fixture, a weather-tight supporting cap having a top threaded attachment opening, depending sides with integral outwardly extending spaced legs having an attachment ring at the outer ends, a lamp adjustably held in the cap, and a transparent ring member secured to the under side of the attachment ring, extending upwardly under the legs, and having a collar to extend upwardly within the lower end of the cap.

7. A lighting fixture comprising a cap member with a top threaded attachment opening, depending sides, legs extending outwardly from the bottom of the sides, and a fixture ring at the ends of the legs; a transparent ring member secured to the ring, underlying the legs, and inserted within the lower edge of the cap; fixture rods extending downwardly within the cap; a lamp socket adjustable on the rods and a lamp carried by the socket and movable to vary the upward illumination through the ring member.

GEORGE ARRAS.

DWIGHT E. WORRELL.
